UNITED STATES PATENT OFFICE.

JOZSEF ZSIDAY, OF NEW YORK, N. Y.

DESIGN FOR A CUSHION-HEEL.

SPECIFICATION forming part of Design No. 31,162, dated July 4, 1899.

Application filed June 9, 1899. Serial No. 719,969. Term of patent 7 years.

To all whom it may concern:

Be it known that I, JOZSEF ZSIDAY, a subject of the King of Hungary, and a resident of New York, borough of Brooklyn, county of 5 Kings, and State of New York, have invented and produced a new and original Design for Cushion-Heels for Boots or Shoes, of which the following is a specification, reference being had to the accompanying drawings, in 10 which—

Figure 1 shows a bottom plan view of a heel for boots or shoes having my design applied thereto. Fig. 2 is a sectional view thereof on a line 2 2 of Fig. 1. Fig. 3 is a top plan 15 view thereof.

The leading or characteristic features of my design consist of a rib or flange around the edge of the heel, the latter being of the ordinary shape or contour, a cavity or depression in the center of the heel, the shape or outline of the cavity being that of the outline or shape of the heel, an opening in the center of the heel, extending entirely through 20 the same, and depressions in the cavity surrounding the central opening, the upper side 25

of the heel having a depression in it extending from the central opening to the edge of said heel.

Referring to the drawings, A represents a cushion-heel for boots or shoes, B a depression the outline of which is that of the outline of the heel, and C a rib or flange around the outer edge. 30

D represents a hole or opening through the center of the heel and from which on the upper side of the heel, as illustrated in Fig. 3, extends a depression E to the edge of said heel. 35

F represents depressions formed in the cavity B and surrounding the central opening D. 40

What I claim is—

The design for a cushion-heel, substantially as herein shown and described.

Signed at New York, in the county of New York and State of New York, this 5th day of June, A. D. 1899. 45

JOZSEF ZSIDAY.
